UNITED STATES PATENT OFFICE

GAETANO CALTABIANO, OF WALLINGTON, NEW JERSEY, ASSIGNOR TO ANDREW FOULDS, JR., OF PASSAIC, NEW JERSEY

CIGARETTE AND CIGAR HOLDER

Application filed May 29, 1930. Serial No. 456,851.

My invention relates to improvements in holders for cigarettes, cigars and the like, and the object of my invention is to produce a device of the character specified containing 5 means for eliminating dust and carbon particles from the smoke drawn therethrough and otherwise purifying and cooling the smoke.

A preferred embodiment of my invention 10 is illustrated in the accompanying drawing, in which,

Figure 1 is a longitudinal section of the preferred form of my improved holder with a cigarette therein,

15 Figure 2 is an enlarged detail thereof, and

Figure 3 is a cross-section on the line 3—3 in Figure 2.

Similar characters of reference refer to 20 similar parts throughout the several views.

The preferred embodiment of my invention 25 illustrated in the drawing, comprises a holder or stem composed of a mouthpiece section 1 and a holder section 2 united by a telescoping joint 3. The holder section 2 is cut out or otherwise shaped interiorly in the usual manner to receive and hold a cigarette 30 or the like 4.

Within the holder is provided a chamber 5 from which a smoke duct 6 leads through 35 the holder section 2 to the cigar or cigarette and a second smoke duct 7 leads from the chamber 5 through the mouthpiece 1.

Within the chamber 5, is provided a hollow shell 8 having its outer wall 9 spaced from 40 the inner wall 10 of the chamber 5 and provided with an inlet orifice 11 in its side wall. A hollow quill or stem 12 is inserted in the shell 8 and extends beyond the orifice 11 thereof. The stem 12 may be longitudinally 45 positioned within the shell 8 by a suitable gasket or packing 13. The stem 12 is of such size as to firmly seat within the smoke duct 7 of the section 1.

The device being thus assembled, the smoke 45 from the burning tobacco will be drawn through the duct 6 to the chamber 5 and will pass thence by a tortuous passage through the orifice 11 to the interior of the shell 8 from 50 which it will be drawn through the quill or stem 12 to the duct 7.

The walls of the shell 8 and stem 12 will act as baffles in the passage of the smoke, dust and carbon, and solid products of combustion will be deposited in the chamber 5 and shell 8 thus purifying the smoke. 55

To clean the device, the sections 1 and 2 are drawn apart or separated and the quill 12 carrying the shell 8, is then withdrawn from the duct 7. The quill 12 may then be withdrawn from the shell 8 and the parts, 60 thus separated, may be conveniently washed and cleaned and the parts reassembled as above described.

Having thus described my invention, what I claim is:

In a device of the character described, a hollow mouth-piece section forming a duct, a quill seated in said duct and secured therein by friction alone, a hollow shell having a side opening intermediate its ends, a gasket 70 at the base of the shell, secured to said quill and holding the said quill and the said shell in spaced relation, and a chambered holder section secured to the mouthpiece section and enclosing said shell with its walls spaced 75 therefrom, whereby is formed a tortuous passage for the passage of smoke.

In testimony whereof I affix my signature.

GAETANO CALTABIANO.
